UNITED STATES PATENT OFFICE.

PAUL HAMMES, OF TREVES, GERMANY.

BOOT BLOCK.

Application filed December 18, 1924. Serial No. 756,708.

To all whom it may concern:

Be it known that I, PAUL HAMMES, a citizen of the German Republic, residing at Treves, Germany, have invented certain new and useful Improvements in Boot Blocks, of which the following is a specification.

Boot blocks have become known which are either designed to merely enlarge the upper of the boot or to enlarge and stretch the upper. The boot blocks of known construction possess the inconvenience that the enlarging of the upper is not carried out in the best practical manner owing to the fact that for this purpose the instep part is composed of two elements which are adjustable parallel with one another but independently of the one of the other. Owing to this construction either the shape of the instep portion of the upper is varied in an undesirable manner, the seams burst, or the tip of the toe part of the boot is deformed.

This invention avoids all these inconveniences and the boot block made according to the invention does not only enlarge the boot in a proper manner, but stretches the same also and it presents the further advantage that the enlarging as well as the stretching can be carried out in any desired succession. The manipulation of the improved boot block is very simple. According to the invention the rear support for the spindle which serves for displacing the heel part of the block in longitudinal direction is rigidly connected with the toe part of the block designed for widening the upper so that the stretching and widening can be carried out independently of the other and alternately in any desired succession without jamming or blocking of the stretching mechanism.

An improved boot block is shown on the accompanying drawing in a perspective view.

The boot block consists of the front part composed of a lower part 1 and of an upper part 2, these parts being connected with one another by means of a hinge 3. To the rear end of lower part 1 of the front part of the block a bar 4 is fixed. In the rear end of the upper part 2 a fork 5 is fixed in which a vertical spindle 6 is loosely mounted and threaded through a lug 7 forwardly projecting from bar 4. In the head of bar

4 a horizontal threaded spindle 8 is swivelled and hingedly mounted. This horizontal spindle traverses a nut 9 which is rotatably mounted in the head 10 of a lever 11 which is pivotally mounted on a pivot pin 12 fixed in a clip 13 rearwardly projecting from the bar 4. The lower end 14 of lever 11 is enlarged to serve as heel block.

The vertical spindle 6 serves to raise or lower the upper part 2 of the front block in order to regulate the widening of the upper. The horizontal spindle 8 serves to stretch the boot by regulating the distance of the heel block 14 from the front block 1, 2.

Owing to the spindles 6 and 8 being both fixed to the vertical bar 4 which is fixed to the lower part 1 of the front block, the block can be used for widening or stretching or for widening and stretching the boot.

I claim:—

A stretching and widening block for boots comprising in combination with the front block composed of two parts hingedly connected the one with the other at the front end, a vertical bar fixed to the rear end of the lower part of the front block, a fork-shaped support fixed in the rear end of the upper part of the front block, a lug forwardly projecting from the upper end of said bar, a vertical spindle threaded in said lug and swivelled into said fork-shaped support and designed to raise or lower the upper part of the front block, a rearwardly projecting clip on said bar, a two-armed lever pivotally mounted in the free end of said clip, the lower end of said lever forming the heel block, a fork-shaped upper end of said lever, a nut rotatably mounted in said upper fork-shaped part of said lever and a horizontal spindle hingedly and rotatably connected with the front end in the upper part of said bar and screwed through said nut so that said lever with the heel block can be adjusted by the rotation of said horizontal spindle.

In testimony whereof I affix my signature in presence of two witnesses.

PAUL HAMMES.

Witnesses:

JOHANN KUSSEL,
WILHELM RUPPENTHAL.
